UNITED STATES PATENT OFFICE.

VOLNEY WAYNE THOMSON, OF EL PASO, TEXAS.

PACKAGE.

Application filed June 2, 1924. Serial No. 717,396.

This invention relates to the packaging of merchandise, particularly the packaging of manufactured tobacco products, such as cigarettes and cigars which are more or less 5 injuriously affected by atmospheric conditions or changes or by repeated handling. In the present instance, by way of example, the invention is illustrated and described as applied to the packaging of cigarettes. It 10 is not limited to this particular purpose, however, since it may well be used in the packaging of other articles, commodities and products.

Cigarettes are subject, more or less, to 15 deterioration due to the action of the atmosphere thereon. Heretofore containers for cigarettes and the like have been made of various materials, such as tin, cardboard, tin-foil, and paper in the form of the common soft wrapper or envelope.

The present invention contemplates a 20 package or container for the cigarettes which opens longitudinally on one side, that is, lengthwise of the contained articles, such as cigarettes or cigars. This is accomplished by providing the package with a longitudinal line of weakening, in the form of perforations, scoring, or the like, which extends entirely across one face of the package and 25 the ends thereof. This perforated or indented line so weakens the material of which the package is formed that it may be easily separated along the line by using a coin or even one's finger nail. No part of the package need be removed or torn away when 30 adapted to be opened as contemplated by this invention. One face and the ends of the package are prepared for opening as above-described, while the opposite face operates 35 as a hinge in the opening and closing of the package until the entire contents are removed, said hinged side, if desired, being reinforced or made so as to cause the hinged sections to close automatically.

40 When the invention is applied to packages or containers for cigars or cigarettes, the cigars or cigarettes are not broken or otherwise injured at their ends in being removed as is the case in packages adapted to be opened at one end. When the package is 45 made in the "soft" form of paper and other flexible materials, it is easily reduced in size by a slight squeeze of the hand as part of the contents is removed. If the package is 50 made of materials intended to protect the

contents from air and moisture, opening of the package by means of the present invention does not reduce the resistance of the air and moisture proof materials which occurs in packages in which a part thereof must be torn away in order to remove the contents. 60

One disadvantage incident to the ordinary form of "pouch" or "soft" package is that it is so constructed as to necessitate the opening or unfolding of a part of the entire end 65 of the wrapper to allow access to and withdrawal of the cigarettes. Even after this has been done, an individual cigarette can only be removed by pinching or grasping the exposed end thereof and withdrawing the cigarette from the package. The cigarettes, especially in a comparatively full package, are tightly packed, and in grasping the ends thereof and removing the cigarettes under such conditions, one or more of them 70 are frequently torn or otherwise damaged. Another disadvantage inherent in the ordinary type of package of this character is that, when it has once been opened, by tearing the revenue stamp and opening the end 75 folds of the mouth of the package, such folds can not readily be restored to and maintain their original closed position. This is so even though the folds be carefully pressed back into place, since they always have a 80 tendency to again spring open and expose the ends of the cigarettes. In many instances this permits the cigarettes to escape from the package into the user's pocket. Likewise, the package being partially 85 opened, the cigarettes will be exposed to the atmosphere and thus become deteriorated. This causes the tobacco in the cigarettes to dry out whereupon it will escape from the open ended package into the user's pocket. 90 By means of the present invention, however, it is intended to overcome these various objections to the ordinary "pouch" package. 95 In the present case, as will appear later, the package after having once been opened, may 100 then be closed and substantially sealed, except perhaps for such slight openings as may be present in the vicinity of the longitudinal slit caused by opening the package along the line of weakening. It is intended that the 105 line of weakening shall be made in the package so as not to interfere with the original sealing of the package, and the latter will thus be maintained in its air and moisture proof condition. The advantages of a pack- 110

age embodying the present invention, in which the package is adapted to be slit longitudinally so that the two sections thereof may be swung open to expose the cigarettes, 5 will be apparent. This permits the cigarettes to be grasped and removed without any chance whatsoever of damaging them, particularly at the ends. Furthermore, it is impossible for the tobacco to fall out of the 10 ends of the cigarettes or the cigarettes to fall out of the package when the hinged sections are properly brought together again.

No radical departure in manufacturing operations or increased expense is involved 15 in the production of packages involving this invention, and yet by means of the same a package is provided, whereby quick access may be had to the cigarettes for their removal without any chance of damaging 20 them.

Reference is had to the accompanying drawing illustrating the application of the invention to a cigarette package. Like reference numerals indicate the same parts 25 throughout the several views, of which,

Figure 1 is a perspective of the package showing the line of weakening in the form of a dotted line;

Fig. 2 a vertical transverse section through 30 the package;

Fig. 3 a perspective of the package after it has been opened; and

Fig. 4 a section similar to Fig. 2, showing the manner in which the package will be 35 closed to retain the cigarettes therein after having once been opened.

The cigarette package shown in the drawing, which is only for the purpose of illustrating an embodiment of the invention, is 40 of the conventional "soft" type, now used by most cigarette manufacturers. The package generally comprises an inner rectangular wrapper or container made up of two co-extensive sheets of thin paper 1 and tin 45 foil 2. The sheets are interfolded at their ends in the usual manner and their inner edges overlapped at 3 to form a substantially air and moisture proof wrapper for the cigarettes.

The inner rectangular wrapper just 50 described is usually contained in a similar outer rectangular wrapper consisting of a fairly heavy paper layer 4, on which appear such decorations and printed matter, in the 55 form of trademarks, etc., as the manufacturer may desire, and an outer layer 5 of transparent, moisture and air proof paper. The layers 4 and 5 of the outer wrapper are folded in at their ends and overlap along 60 their inner edges on one side of the package, as shown at 6, in order to form the completed package. The outer layer 5 of transparent paper may be omitted, if found desirable, in which case the package will still 65 serve to sufficiently protect the cigarettes

from atmospheric conditions, due to the nature and number of the remaining layers of material of which the package is made.

The line of weakening, by means of which the package may be ruptured longitudinally, 70 is shown in Fig. 1 in the form of a dotted line 7, which extends centrally and longitudinally across one face 8 of the package and the ends 9 and 10. Preferably, the line of weakening 7 is in the form of perforations, but it may be made by indenting the material of the package, so as to preclude any possibility of the atmosphere affecting 75 the contents. It has also been found desirable to provide the line of weakening only 80 in the outer wrapper, consisting of the paper layers 4 and 5.

As shown in the drawing, the line of weakening 7, is made centrally of the face 8 of the package, although it need not necessarily 85 be so located, and just above and in line with or near the edge of the outer overlapping portion of the inner wrapper. Thus it will be seen that when the package is broken or ruptured along the line of weakening 90 7 and the sections 11 and 12 thereof are thrown back, as shown in Fig. 3, the outer overlapping edge portion of the inner wrapper just mentioned will not be damaged or disturbed. The inner overlapping 95 edge portion of the inner wrapper, however, will be withdrawn from the opposite section of the package, as is clearly shown in Fig. 3. Inasmuch as the line of weakening 100 7 extends only across the face 8 and the ends 9 and 10 of the package, when the package is broken along this line and the divided sections 11 and 12 thrown back (Fig. 3), the central portion 13 of the under face 14 of the package, opposite that portion of the line of 105 weakening 7 on face 8 of the package, will serve as a hinge for the sections. This central portion 13 of the under face 14, it is to be noted, comprises all four layers of material which go to make up both the inner and outer wrappers. This portion of the package, therefore, is quite strong and will serve 110 as a hinge for the sections of the package until the entire contents thereof are removed without any fear of tearing or rupturing at 115 this point. Also due to the number of thickness of material in portion 13, the same will be comparatively stiff and yet sufficiently resilient to tend to close or bring together the hinged sections of the package after it 120 has been opened. This aids materially in preventing the cigarettes falling out of the package.

It is obvious from Fig. 3 of the drawing, 125 that the cigarettes may be grasped and removed from the package with much greater facility and with much less chance of damage thereto than is the case with the common type of package in which one of the ends 9 or 10 of the package, or a portion 130

thereof, is torn away and the cigarettes removed by their ends.

The cigarettes remaining in the package after it has once been opened are contained in the sections of the package so that there is no chance of the tobacco leaking out of their ends and into the user's pocket. After the package has once been opened as above described and cigarettes removed therefrom and it is desired to close it again, the sections of the package are swung towards each other about the hinged portion 13 and the inner overlapping edge portion or flaps of the inner wrapper then enters the opposite section 12 of the package, possibly assisted by the user's fingers, until the severed edges of the sections are brought together into their original abutting relation. The manner in which the sections of the package are brought into closed condition and the overlapping edge portion of the inner wrapper enters the opposite hinged section of the package is clearly shown in Fig. 4.

It is to be noted that the re-entrance of said overlapping portion into the package section 12 is facilitated by reason of the fact that certain of the cigarettes which might interfere with this have been removed.

The sections 11 and 12 of the package having been brought back into a closed position, it will be seen that not only is the package placed in such condition that neither the cigarettes nor the tobacco can escape therefrom, but also the package is again practically rendered air and moisture proof so as to protect the cigarettes.

What is claimed is:

1. A merchandise package comprising, in combination, an inner tubular wrapper having its longitudinal edge portions overlapping each other on one face of the package and its end portions interfolded to form a closed container in such a manner as to facilitate the separation of the folds on the three sides, and an outer wrapper completely enveloping said inner wrapper, said outer wrapper being provided with a line of weakening extending across said face and the ends of the package, in close proximity to said overlapping portions of the inner wrapper, whereby the folded portions and the overlapping portions of the inner wrapper are readily separated when the outer wrapper is broken.
- 55 2. A rectangular merchandise package, having front, rear, side and end faces, com-

prising, in combination, an inner tubular wrapper having its longitudinal edge portions overlapping each other on the front face of the package and its end portions interfolded to form a closed container, and an outer wrapper completely enclosing said inner wrapper, said outer wrapper being provided with a line of weakening extending longitudinally of the front face of the package, adjacent and substantially parallel to the edges of said overlapped portions of the inner wrapper, and across the ends of the package to the rear face thereof whereby the folded portions and the overlapping portions of the inner package are readily separated when the outer package is broken.

3. A rectangular cigarette package comprising, in combination, an inner tubular wrapper of air and moisture-proof material, having its longitudinal edge portions overlapping each other on one face of the package and its end portions interfolded to form a closed container for cigarettes adapted to be disposed longitudinally thereof, and an outer wrapper provided with a line of weakening extending across said face and the ends of the package, in close proximity and parallel to the edge of the outer of said overlapping edge portions of the inner wrapper, to permit the ready separation of the folded portions and the overlapping portions of the inner wrapper when the outer wrapper is broken whereby a cigarette may be removed in a direction perpendicular to the face of the package.

4. A merchandise package comprising in combination an outer wrapper, said outer wrapper being provided with a line of weakening extending longitudinally across the face of the package and across the ends, an inner tubular wrapper having its longitudinal edge portions overlapping each other on said face of the package in close proximity to said line of weakening on the outer wrapper and its end portions likewise folded in such a manner as to facilitate separation thereof after the outer wrapper is broken whereby the articles are protected, and the shape of the container is retained when the package is again brought to a closed position by the overlapping portions and the folded portions.

In testimony whereof I have signed my name to this specification.

VOLNEY WAYNE THOMSON.
